TUFTING DEVICE

Samuel P. Parker, La Grange, Ga., assignor to
Callaway Mills, La Grange, Ga., a corporation
of Georgia

Application July 8, 1946, Serial No. 682,017

16 Claims. (Cl. 112—80)

1 This invention relates to devices for the insertion of tufts in fabrics for decorative and other purposes and is concerned more particularly with a novel manually controlled tufting instrument of the type that is sometimes referred to as an "embroidery pencil" and includes a reciprocating needle for inserting the tuft yarn and a presser foot for preventing the last inserted loop from being withdrawn upon insertion of the next one. The new pencil is power driven, and it is so constructed that the operator may insert tuft loops by moving the pencil in any direction over the fabric without the necessity of rotating the pencil to insure that the presser foot will always trail behind the needle in position to perform its intended function. The pencil is, accordingly, much easier to handle than prior similar pencils and by its use, fabrics with intricate tuft designs or with tufts extending along curved lines may be produced much more rapidly than with prior implements.

In its preferred form, the new pencil includes a casing, within which a needle bar is mounted for reciprocation lengthwise of the casing. The bar carries a needle projectible out of one end of the casing, as the bar reciprocates, and a presser foot is mounted for rotary movement at that end of the casing and extends laterally from the path of travel of the needle. The needle bar is free to rotate about its axis and is connected to the presser foot to move angularly therewith. The presser foot and needle thus have a fixed angular relation and the foot extends rearwardly from the needle. As the pencil is moved over the fabric in any direction, the drag of the presser foot on the fabric causes the foot to trail behind the needle at all times and this causes the needle to enter the fabric with the presser foot always to the rear of the needle in position to hold the last inserted loop against withdrawal upon the next insertion of the needle.

For a better understanding of the invention, reference may be made to the accompanying drawing, in which:

Fig. 1 is a view in longitudinal section of one form of the embroidery pencil of the invention; and

Fig. 2 is a sectional view on the line II—II of Fig. 1.

The pencil illustrated in the drawing comprises a casing 10 of generally tubular shape and made of any suitable material. The casing is formed with an end 11 of tapered outer diameter, and its opposite end is closed by a plug 12 threaded in place. A slide 13 is mounted

2 within the casing for lengthwise movement, and a rod 14 is attached to the slide and extends out through a bore through the plug 12. The rod is adapted to be connected to means for reciprocating the slide and may, for example, be part of a flexible shaft enclosed within the usual flexible casing 15 and connected to an eccentric pin 16 on a disk 17 mounted on a drive shaft 18.

A ball bearing 19 is mounted in the slide and the inner ring of the bearing receives and is secured to one end of a hollow needle bar 20. The bar thus reciprocates with the slide but is free to move angularly relative thereto in the ball bearing.

15 A presser foot 21 is mounted at the tapered end of the casing and is provided with a tubular extension 22, which enters the end of the casing and receives a portion of the needle bar. The tube and presser foot are free to rotate about **20** the axis of the casing but held against longitudinal displacement. For this purpose, the tube may be formed with a circumferential channel 23, in which a ball 24 is held by means of a screw 25 threaded through the wall of the casing.

25 The needle bar carries a tubular needle 26 at its free end, and the needle is projectable out of the casing, when the needle bar is reciprocated by the slide. The free end of the needle is cut off at an angle to give it a beveled rear face 27, and the presser foot should extend rearwardly from the needle at all times in order that it may function properly. The presser foot is, accordingly, held in proper position and against angular movement relative to the needle bar, and, for **30** this purpose, that portion of the needle bar, which enters the tube 22, is square or otherwise non-circular in outline and the bore of the tube 22 is correspondingly formed.

35 The yarn 28 is supplied to the pencil through a passage 29 through the plug 12, and passes from the plug through the hollow needle bar and thence through the needle to project beyond the pointed end thereof.

40 In the operation of the pencil, it is placed on the fabric with the presser foot 21 in contact with the surface of the fabric and with the needle over the spot where the first tuft is to be inserted. As the slide, bar, and needle move down, the needle enters the fabric, carrying the yarn **45** with it. A loop of the yarn is inserted through the fabric by the penetration of the fabric by the needle and the retraction of the latter, and, upon the insertion of a loop, the pencil is advanced to bring the needle to the next point where **50** an insertion is to be made. As the pencil is

moved over the fabric, the presser foot is kept in trailing position to the rear of the needle by the frictional drag of the foot along the fabric, regardless of the direction in which the pencil may be moved. The foot thus always overlies the last inserted loop and prevents that loop from being pulled out of the fabric, when the needle makes its next insertion.

In prior embroidery pencils, the needle and presser foot have not been free to rotate about the axis of the pencil and the presser foot and needle bar have not been connected together against relative angular movement. As a result, it is necessary to rotate such a pencil, when it is moved along a curved path, or any other change of direction is made, to insure that the presser foot will always be to the rear of the needle. The operator of such a pencil must, accordingly, pay strict attention to the position of the presser foot at all times. The new pencil is so constructed that the presser foot is always in trailing position, as the pencil is moved over the goods, and the operator may, accordingly, insert tufts in any direction without turning the pencil to insure that the presser foot will be properly positioned.

I claim:

1. An embroidery pencil which comprises a casing, a needle bar mounted within the casing for rotary movement and also for reciprocation lengthwise of the casing, a hollow needle attached to the bar and projectable out of one end of the casing during reciprocation of the bar, and a presser foot mounted at said end of the casing for movement about the axis of the bar, the presser foot extending laterally from the casing, the bar being free to reciprocate relative to the presser foot but being connected for rotary movement in unison therewith.

2. An embroidery pencil which comprises a casing, a needle bar mounted within the casing for rotary movement and also for reciprocation lengthwise of the casing, a hollow needle attached to the bar and projectable out of one end of the casing during reciprocation of the bar, a presser foot mounted at said end of the casing for movement about the axis of the bar, the presser foot extending laterally from the casing, the bar being free to reciprocate relative to the presser foot but being connected for rotary movement in unison therewith, and a rod attached to the needle bar and projecting out the other end of the casing.

3. An embroidery pencil which comprises a casing, a needle bar mounted within the casing for rotary movement and also for reciprocation lengthwise of the casing, a hollow needle attached to the bar and having an end with a beveled face projectable out of one end of the casing during reciprocation of the bar, and a presser foot mounted at said end of the casing for movement about the axis of the bar, the presser foot extending laterally from the casing directly away from the beveled face on the needle and being connected to the bar for rotary movement in unison therewith.

4. An embroidery pencil which comprises a casing, a slide mounted within the casing for reciprocation lengthwise of the casing, a needle bar mounted within the casing for rotary and longitudinal movement and connected to the slide for reciprocation therewith, a hollow needle attached to the bar and projectable out of one end of the casing during reciprocation of the bar, and a presser foot mounted at said end of the casing for movement about the axis of the bar only, the

presser foot and bar being connected for rotary movement in unison and the bar being freely reciprocable relative to the presser foot.

5. An embroidery pencil which comprises a casing, a slide mounted within the casing for reciprocation lengthwise of the casing, a needle bar mounted within the casing for rotary and longitudinal movement and connected to the slide for reciprocation therewith, a hollow needle attached to the bar and projectable out of one end of the casing during reciprocation of the bar, a presser foot mounted at said end of the casing for movement about the axis of the bar only, the presser foot and bar being connected for rotary movement in unison and the bar being freely reciprocable relative to the presser foot, and a rod connected to the slide and projecting out of the other end of the casing.

6. An embroidery pencil which comprises a casing, a slide mounted within the casing for reciprocation lengthwise of the casing, a bearing carried by the slide, a needle bar mounted within the casing for rotary and longitudinal movement, the bar having a portion within the bearing and being reciprocable with the slide, a hollow needle attached to the bar and projectable out of one end of the casing during reciprocation of the bar, and a presser foot mounted at said end of the casing for movement about the axis of the bar only, the presser foot and bar being connected together against relative angular movement and the bar being freely reciprocable relative to the presser foot.

7. An embroidery pencil which comprises a casing, a presser foot having a tubular extension entering one end of the casing, the foot extending laterally from said end of the casing and being freely rotatable about the axis of said tubular extension but held against movement lengthwise of the casing, a needle bar mounted within the casing and having a portion within said tubular extension, the bar being freely reciprocable endwise and freely rotatable in the casing, the bar being connected to the presser foot to rotate therewith, and a needle carried by the bar and lying within said tubular extension, the needle being projectable out of the extension during reciprocation of the bar, the drag of the presser foot upon the fabric being embroidered causing the presser foot to assume a trailing position in relation to the needle during the operation of the pencil.

8. An embroidery pencil which comprises a casing, a tube mounted within one end of the casing against movement lengthwise of the casing but free to rotate, a presser foot connected to the end of the tube and projecting laterally from said end of the casing, a needle bar mounted within the casing for endwise movement and having a portion entering the tube, the bar being free to move lengthwise of the tube but connected thereto against relative angular movement, and a hollow needle connected to the bar and extending through the tube.

9. An embroidery pencil which comprises a casing, a tube mounted within one end of the casing against movement lengthwise of the casing but free to rotate, a presser foot connected to the end of the tube and projecting laterally from said end of the casing, a needle bar mounted within the casing for endwise movement and having a portion entering the tube, the bar being free to move lengthwise of the tube but connected thereto against relative angular movement, and a hollow needle connected at one end to the bar and

extending through the tube, the free end of the needle having a beveled face away from which the presser foot directly extends.

10. An embroidery pencil which comprises a casing, a hollow needle bar mounted within the casing for endwise and rotary movement, a presser foot projecting laterally from the casing at one end and having a part encircling the bar and connected thereto for angular movement with the bar, the foot being held against movement lengthwise of the casing, and a hollow needle mounted at one end on the needle bar and movable therewith.

11. An embroidery pencil which comprises a casing, a slide mounted within the casing for reciprocating movement lengthwise of the casing, a rod attached to the slide and extending out one end of the casing, a bearing carried by the slide, a hollow needle bar mounted in the bearing for rotary movement relative to the slide, the bar extending lengthwise of the casing and being connected to the slide for movement therewith, a hollow needle attached to the bar and having an end projectable out of one end of the casing during reciprocation of the slide, a presser foot mounted at said end of the casing and extending laterally from the path of travel of the needle, and means connecting the bar and foot for angular movement in unison while permitting free reciprocation of the bar relative to the foot.

12. An embroidery pencil which comprises a casing, a needle bar mounted within the casing for rotary and endwise movement, the bar having a portion of non-circular outline, a tube mounted within one end of the casing and having a bore receiving said portion of the bar and of a cross-sectional shape corresponding to the outline of said portion, the tube being free to rotate within the casing but held against longitudinal movement, a needle mounted at the end of said portion of the bar and movable through the tube, and a presser foot attached to the tube and extending rearwardly from the needle.

13. In an embroidery pencil, the combination of a needle bar mounted for free longitudinal and rotary movement, a hollow needle attached to the needle bar to move therewith, the needle having a free end cut off at an angle to provide an inclined rear surface, and a presser foot mounted for rotary movement and connected in fixed angular relation to the needle bar, the presser foot lying to the rear of the needle.

14. In an embroidery pencil, the combination of a needle bar mounted for longitudinal and rotary movement, a hollow needle carried by the bar and having a rear beveled face, and a presser foot mounted for rotary movement and

connected in fixed angular relation to the needle bar and needle, the foot extending rearwardly from said face on the needle, the drag of the presser foot upon the fabric being embroidered causing the presser foot to assume a trailing position in relation to the needle and the presser foot causing the needle bar and needle to rotate with it.

15. In an embroidery pencil, the combination of a hollow needle mounted in the casing for reciprocation and for rotary movement about its axis, the needle having a free end cut off at an angle to provide an inclined surface, said end of the needle being exposed beyond one end of the casing during the reciprocation of the needle, a presser foot mounted at said end of the casing for free rotary movement about the axis of the needle, means connecting the presser foot and needle for rotary movement in unison about the axis of the needle and with the presser foot lying to the rear of the inclined surface of the needle, and means for reciprocating the needle, the drag of the presser foot on the fabric being embroidered causing the presser foot to assume a trailing position relative to the needle and to maintain the needle with its inclined surface facing rearwardly.

16. In an embroidery pencil, the combination of a hollow needle mounted in the casing for reciprocation and for rotary movement about its axis, the needle having a free end cut off at an angle to provide an inclined surface, said end of the needle being exposed beyond one end of the casing during the reciprocation of the needle, a presser foot mounted at said end of the casing for free rotary movement about the axis of the needle, and having a surface adapted to engage the fabric being embroidered and extending normal to the axis of the needle, means connecting the presser foot and needle for rotary movement in unison about the axis of the needle and with the presser foot lying to the rear of the inclined surface of the needle, and means for reciprocating the needle, the drag of the presser foot on the fabric being embroidered causing the presser foot to assume a trailing position relative to the needle and to maintain the needle with its inclined surface facing rearwardly.
